UNITED STATES PATENT OFFICE.

HARRY S. DUNBAR, OF CLEVELAND, OHIO.

SHADE-ROLLER BRACKET.

No. 823,997.

Specification of Letters Patent.

Patented June 19, 1906.

Application filed October 20, 1905. Serial No. 283,611.

To all whom it may concern:

Be it known that I, HARRY S. DUNBAR, a citizen of the United States, residing at Cleveland, in the county of Cuyahoga and State of Ohio, have invented new and useful Improvements in Shade-Roller Brackets, of which the following is a specification.

When an ordinary shade-roller bracket is set at the usual place at the top of the casing, it covers the upper sash and obstructs, to a large extent, any ventilation which could otherwise be secured by opening the upper sash.

The object of the present invention is to provide a shade-roller bracket which can be quickly and readily raised or lowered, so that when lowered a space is left at the top through which ventilation can be effected. This object is accomplished by means of a bracket having swinging pieces which carry the shade-roller and which can be swung up or down for the purpose indicated.

The invention is illustrated in the accompanying drawings, Figure 1 being a front view of part of a window provided with the improvement, the shade-roller being in the upper position. Fig. 2 is a similar view with the roller lowered. Figs. 3 and 4 are side views of a bracket in lowered and raised position, respectively.

Referring specifically to the drawings, 6 indicates the window-casing and 7 the shade-roller. Each bracket consists of a plate 8, which is attached to the case by means of screws at 9, with an arm 10 projecting forwardly from said plate and having pivoted to its outer end at 11 a swinging plate 12, which is provided with a hole 13 to receive the end of the spindle of the shade-roller. Struck out from the upper edge of the plate 10 is a stop 14, against which the plate 12 strikes

and stops when it is swung up. The outer end of the arm 10 is dropped, as shown, to bring the plate 12 in proper position to strike the stop and to allow the shade to hang at the proper place. The spindles of the shade-roller are inserted in the holes 13 in the usual manner. When in raised position, as shown in Figs. 1 and 4, the shade covers the whole window, the same as usual. When ventilation at the top of the window is desired, the shade may be pulled out sharply toward the horizontal to swing the plates 12 forwardly, so that they will drop to the lower position, causing the shade to hang several inches below the top of the upper sash, and when said sash is opened ventilation is not obstructed. The shade-roller can again be swung up by hand when desired. In case a roller is hung too high to be conveniently reached by hand it can be swung either up or down by means of a hooked rod or other implement provided for the purpose.

Having thus described my invention, what is claimed as new, and desired to be secured by Letters Patent, is—

A shade-roller bracket comprising a horizontally-extending supporting-arm having a projecting stop, and a plate pivoted at its inner end to the outer end of the arm and having in its free end an opening to receive the roller-spindle, and constructed to swing below or above the arm and to strike the stop when swung up.

In testimony whereof I have signed my name to this specification in the presence of two subscribing witnesses.

HARRY S. DUNBAR.
